UNITED STATES PATENT OFFICE.

CHARLES E. BATHRICK, OF CHICAGO, ILLINOIS, ASSIGNOR TO FREDERICK C. AUSTIN,
OF CHICAGO, ILLINOIS.

EXCAVATING-MACHINE.

1,023,356.

Specification of Letters Patent.

Patented Apr. 16, 1912.

Application filed January 12, 1911, Serial No. 602,360. Renewed September 5, 1911. Serial No. 647,799.

To all whom it may concern:

Be it known that I, CHARLES E. BATHRICK, a citizen of the United States of America, and resident of Chicago, Cook county, Illinois, have invented a certain new and useful Improvement in Excavating - Machines, of which the following is a specification.

My invention relates to machinery of the kind employed for general excavating purposes, such as grading, but more particularly for building ditches, and for other similar purposes requiring a level road over which the machine can advance in the direction of the excavation. For example, a drag line excavator is of this general character, and when used for this purpose requires, very often, the leveling of the ground ahead or in advance of the machine. This, of course, must be done by a separate machine, under the conditions prevailing prior to my invention, and usually with some difficulty and at considerable expense.

My invention contemplates, therefore, a combination dipper and drag line excavator; the dipper being disposed at the forward end of the machine to level or otherwise prepare the ground over which it must travel, and the drag-line bucket being arranged to operate at the rear of the machine, whereby the one machine is sufficient for both purposes, and the work of preparing or leveling the ground and then forming a ditch therein is expedited and rendered more satisfactory in general. The nature and advantages of my invention will, however, hereinafter more fully appear.

In the accompanying drawings—Figure 1 is a side elevation of the front or dipper end of a machine embodying the principles of my invention. Fig. 2 is a side elevation of the middle portion of said machine. Fig. 3 is a side elevation of the rear or drag-line end of the machine.

As thus illustrated, and referring to Fig. 1, the front of the body A has a turn-table B thereon, which turn-table has a boom b pivoted at b' and provided at its middle with a pivoted arm b² that carries a dipper b³ of any suitable character. The said dipper arm is operated or controlled by a rope b⁴ that is attached to the mouth of the dipper b³, and which is arranged over the sheave b⁵ on the end of the boom. From here the said rope then extends rearward along the boom to the sheave b⁶ on the turn-

table, and then downward around the sheave b⁷, the vertical portion of the rope between the sheaves b⁶ and b⁷ being coincident with the axis of the turn-table. The boom is raised and lowered by a rope b⁸ that runs over sheaves b⁹ and b¹⁰ and b¹¹, the latter two on the mast C, and the former on the end of the boom. The ropes or lines b⁴ and b⁸ are operated by a drum or winding mechanism D, which latter may be of any well known character and controlled in any suitable manner, being driven by an engine d through the medium of a suitable connection.

The rear end of the body A has a turn-table E upon which a boom e is pivoted at e'; said boom having its outer end provided with sheaves e² and e³, and with a third sheave e⁴ for the rope or line e⁵ by which the boom is raised and lowered. This rope or line extends over the sheaves e⁶ and e⁷ on the mast e⁸, which latter has upper and lower sheaves e⁹ and e¹⁰. The turn-table E has a sheave e¹¹, and directly below, on the body A, there is a sheave e¹². The drag-line bucket F may be of any suitable, known or approved construction, and is operated by a drag-line f that extends over and under the sheaves e¹¹ and e¹², the vertical portion of this line being coincident with the axis of the turn-table F. The bucket has a hoist line f' that extends upward over the sheaves e² and e¹⁰, and a dumping line f² that extends upward and over the sheaves e³ and e⁹, the hoist line being attached to the rear edge of the mouth of the bucket, and the dumping line being attached to the bottom of the bucket. The lines or ropes f' and f² lead to the drum or winding mechanism G, while the lines or ropes f and e⁵ lead to the drum or winding mechanism H, which are driven by the engine d and controlled by any suitable means. The line f runs between the guide sheaves f³ on the boom.

The masts C and e⁸ have their upper ends connected by a rod I, and said masts are also connected by the crossed braces J, whereby a strong superstructure or frame is insured.

The body A is supported on wheels K or other suitable devices for enabling the machine to move forward in the direction desired for the ditch.

The mode of operation, in making a ditch x with the drag-line bucket F, is as follows: The dipper b³ is employed for smoothing off

or leveling the ground in front of the machine, any suitable expedient being employed for causing the dipper to dump its load. This is done as the machine moves forward from time to time, and at the same time the bucket F is operated by the drag-line f to gradually form a trench or ditch α in the ground in rear of the machine. Thus the two operations, the leveling ahead of the ground, and the formation behind of the ditch, are accomplished by one and the same machine. This means, of course, that fewer attendants are necessary than heretofore, and that a saving is effected in the cost 15 of constructing the ditch.

What I claim as my invention is:

1. In an excavator, a body, a turn-table with a drag-line bucket equipment at one end of said body, and a turn-table with a 20 dipper equipment at the other end of said body.
2. In an excavator, a body, a ditching apparatus at the rear end of said body, and an excavating apparatus on the forward end of said body.
3. In an excavator, a body, a turn-table with a drag-line bucket equipment at one end of said body, a turn-table with a dipper equipment at the other end of said body, 30 and a power plant and winding drum mechanism for the entire excavator, carried on the middle portion of said body.
4. In an excavator, a body, a ditching apparatus at the rear end of said body, an ex-

cavating apparatus on the forward end of 35 said body, and a power plant and winding drum mechanism for the entire excavator, carried on the middle portion of said body.

5. In an excavator, a body, a turn-table with a drag-line bucket equipment at one 40 end of said body, a turn-table with a dipper equipment at the other end of said body, a mast for each end of the excavator, and brace members connecting said masts together, wheels for said body, an engine near 45 the forward end of the body, a winding drum mechanism between the engine and the rear end of the body, there being comprised in the foregoing a boom overhanging each end of said body.

6. In an excavator, a body, a ditching apparatus at the rear end of said body, an excavating apparatus on the forward end of 50 said body, a mast for each end of the excavator, and brace members connecting said 55 masts together, wheels for said body, an engine near the forward end of the body, a winding drum mechanism between the engine and the rear end of the body, there being comprised in the foregoing a boom overhanging each end of said body.

Signed by me at Chicago, Illinois, this fifth day of January, 1911.

CHARLES E. BATHRICK.
